UNITED STATES PATENT OFFICE.

WESLEY B. KRAFT, OF MILAN, KANSAS.

ELECTROMAGNETIC PIANO-PLAYER.

No. 879,879.

Specification of Letters Patent.

Patented Feb. 25, 1908.

Application filed June 19, 1906. Serial No. 822,462.

To all whom it may concern:

Be it known that I, WESLEY B. KRAFT, a citizen of the United States, residing at Milan, in the county of Sumner and State of Kansas, have invented certain new and useful Improvements in Electromagnetic Piano-Players, of which the following is a specification.

This invention relates to instruments of that character known as piano players for playing pianos, organs, etc., and my object is to produce an instrument in which the operation of the musical instrument keys is effected through the alternate energization and deenergization of electro-magnets.

A further object is to produce an instrument of this character which operates efficiently and reliably, can be easily and quickly placed in or removed from operative relation to the instrument to be played and which is of simple, strong, durable and inexpensive construction.

With these general objects in view and others as hereinafter appear the invention consists in certain novel and peculiar features of construction and organization as hereinafter described and claimed; and in order that it may be fully understood reference is to be had to the accompanying drawings, in which—

Figure 1, is a top plan view of a portion of a piano and a player embodying my invention. Fig. 2, is a vertical section on the line II—II of Fig. 1. Fig. 3, is a view of a portion of a perforated note sheet for use with said player. Fig. 4, is a diagrammatic view showing the electric circuits of the player. Fig. 5, is a side view, partly broken away, of a portion of a modified form of the player. Fig. 6, is an enlarged section taken on the dotted line VI of Fig. 2. Fig. 7, is an enlarged detail perspective view of a device for breaking the electric circuits of the player.

In the said drawings, 1 indicates an oblong rectangular box which preferably slightly exceeds in length the key-board of a piano. 2 indicates a longitudinal series of electro-magnets in said box spaced to correspond with the spacing of the white keys of a piano. 3 indicates a corresponding series of electro-magnets in the box spaced to correspond to the spacing of the black keys and arranged preferably rearward of the white-key magnets.

4 and 5 indicate blocks secured rigidly upon the front wall of the box and hinged as

at 6 to said blocks are key strikers 7 and 8 respectively, said key strikers being arranged respectively over magnets 2 and 3 and projecting rearwardly over and beyond the rear wall of the box, each key striker being provided at its rear extremity and underside with a cushion 9 and near its hinge point with an armature 10, to coöperate with its respective electro-magnet, it being noted in this connection that the black-key strikers have their rear portions arched at 11, in order to avoid contact with the white keys of the piano.

12 indicates standards rising from the front of the box by preference and disposed a distance apart slightly exceeding the width of the note sheet hereinafter identified, to be employed in the instrument. Ordinarily the distance between the standards will approximate fifteen inches, and mounted upon said standards is a casing 13.

14 indicates a horizontal shaft journaled in suitable bearings in the side walls of casing 13 and rigidly secured on said shaft is a feed roller 15 provided with guide flanges 16 at its ends to assist in guiding the note sheet.

17 indicates a roller spaced with relation to roller 15 to coöperate with the same in feeding the note-sheet through the instrument and grooved or reduced at its ends at 18 by preference to receive the flanges 16 of roller 15.

19 indicates the shaft of roller 17, journaled in bearings 20, arranged for vertical movement in slots 21, in the side walls of the casing 13, springs 22 being secured in said slots and exerting a downward pressure on bearings 20, to cause the roller 17 to press the note sheet against roller 15.

23 indicates a cross bar connecting the side walls of the casing forward of roller 15 and preferably curved at its upper side and provided at its ends with upwardly projecting flanges 24 in the vertical plane of the roller flanges 16 to coöperate with the latter in preventing lateral movement of the note sheet.

25 indicates a contact bar carried by and preferably at the rear edge of bar 23 and electrically connected by a conductor 26 to one pole of a battery or other source of electric supply 27, the other pole of the battery being connected by conductors 28 to one terminal of the coils of each electro-magnet.

29 indicates an insulating bar connecting the side walls of the casing 13, and 30 bars

carried by the insulating bar corresponding in number to the electro-magnets; conductors 31 connect said bars 30, with the other terminals of the coils of said magnets. Pivot 5 oted at 32 for movement in a vertical plane to bars 30, are contact fingers 33 having their opposite ends adapted to yieldingly engage the contact bar 25 and complete the circuit through the battery and the magnets when 10 not insulated from the said bar 25 by the note sheet or held elevated by the angular rock bar 34, having its cylindrical spindles 35 journaled in the side walls of casing 13. At one end the bar is provided with a flattened 15 surface 36, and in the vertical plane of said surface the contiguous wall of the casing 13 is provided with a spring 37. Normally the spring by engagement with the flat side of the rock bar holds the latter as shown in Fig. 20 2, so as not to interfere with the engagement of the pivoted fingers with contact bar 25 when the former are not elevated and insulated from said bar by the note sheet. When it is desired to break the electric circuit 25 through all of the fingers and thus deenergize all of the magnets, the handle 38 is grasped and turned to rock said rock bar and cause it to simultaneously elevate all of the fingers 33 and hold them above the plane of 30 the contact bar.

The box 1 may be supported in any suitable manner, that is may be provided with supporting legs 39, so that it can be placed up against the front bar 40 of the piano as 35 shown in Fig. 1 with its key strikers 7 overhanging the white keys 41 and its key strikers 8 overhanging the black keys 42 of the piano, and to effectually maintain the player in the relation described, I preferably provide the 40 ends of the box 1 with eye-bolts 43 to which are pivoted hooks 44 for engagement with eye-bolts 45 secured in the blocks 46 at opposite ends of the keyboard of the piano.

After the player is secured as explained, 45 the desired perforated note sheet 47 is fed rearwardly over bar 23 and contact bar 25 and between feed rollers 15 and 17. If it is desired to repeat the music, I preferably detachably secure the ends of the note sheet 50 together, the preferred method being to provide the rear end with a transversely alined series of slits 48, and the other end with a corresponding series of tongues 49, to be slipped through the slits 48 and bent back so 55 as to project rearwardly at the inner side of the rear end portion of the note sheet. As thus arranged the tongues will flatten out as they pass over bar 23, bar 25 and between the feed rollers, and offer no resistance to the 60 proper movement of the note sheet, and thus permit the music to be repeated as many times as desired.

Assuming that the note sheet is in place and the parts otherwise properly assembled, 65 the rollers are caused to turn in the direction

indicated by the contiguous arrows Fig. 2. They can be turned by hand if desired, but preferably will be turned by means of a spring motor or clockwork as shown in Fig 5. In said figure one end of the shaft 14 is 70 provided with a pulley 50 connected by a belt 51 with a pulley 52 journaled on the shaft or spindle of a suitably journaled roller 53 and provided with a gear wheel 54 meshing with a large gear wheel 55 journaled on a 75 shaft 56. Shaft 56 is adapted to be journaled in the casing and mounted upon and secured to the shaft at its inner end in the usual manner (not shown) is a spring 57 secured at its outer end to a pin 58 rigid with the 80 contiguous standard 12.

59 is a ratchet rigid on the shaft, and 60 a pivoted pawl carried by wheel 55 and held yieldingly engaged with the ratchet by a spring 61. By means of this spring motor 85 25 and connections the feed rollers 15 and 17 will operate to effect the travel of the perforated note sheet and as the perforations therein pass over the contact bar the respective contact fingers 33 project through said 90 openings and engage said bar and therefore complete an electric circuit, the result being the magnet attracts its armature and causes the key striker carrying the same to strike and depress the corresponding key of the 95 piano.

With the parts arranged as described the operation will continue so as to reproduce the same selection as many times as desired, it being understood of course that a suitable 100 governor or a clock work escapement, not shown because of common and well-known construction, will be employed to regulate the speed of the feed rollers. The instrument will also be provided with a dog 62 or its 105 equivalent, to lock the spring against unwinding when not in use.

Where it is desired to employ note sheets of that character in common use which roll and unroll alternately, that is, unwind from 110 one roller and wind upon another and then reverse such movement, I pivot arms 63 carrying a journaled roller 64, on the instrument frame as at 65, and provide springs 66 to hold said roller pressed toward roller 53, 115 the front end of the note sheet numbered 67 in this instance, being adapted to be detachably secured to roller 64 in any suitable manner, the opposite end of the note sheet being permanently mounted upon a roller 68 120 having its shaft 69 journaled at the lower ends of slots 70 through which the said roller 68 is withdrawn when it is desired to introduce another equipped with a different piece of music, and to rewind the note sheet from 125 roller 64 onto roller 68 the shaft of the latter is provided with a small gear wheel 71 meshing with a large gear 72 provided with a crank handle 73.

From the above description it will be ap- 130

parent that I have produced a piano playing mechanism possessing the features of advantage enumerated as desirable and I wish it to be understood that I do not desire to be restricted to the exact details of construction shown and described as obvious modifications will occur to one skilled in the art.

Having thus described the invention what I claim as new and desire to secure by Letters Patent, is:—

1. A piano player, comprising electro magnets, lever hammers, armatures for said magnets carried by said hammers, a perforated note sheet, feed rollers therefor, a contact bar over which the note sheet travels, pivoted fingers adapted to project through the note sheet perforations and engage said bar, a source of electric supply in circuit with said magnets, contact bar and fingers, means for operating the feed rollers, and an angular rock bar arranged adjacent to and bearing directly against the contact fingers for moving and holding said fingers out of contact with said contact bar.
2. A piano player, comprising electro magnets, lever hammers, armatures for said magnets carried by said hammers, a perforated note sheet, feed rollers therefor, a contact bar over which the note sheet travels, pivoted fingers adapted to project through the note sheet perforations and engage said bar, a source of electric supply in circuit with said magnets, contact bar and fingers, means for operating the feed rollers, an angular rock bar bearing against the contact fingers for moving and holding said fingers out of contact with said bar, and means for

yieldingly holding the rock bar in position to permit the fingers to engage the contact bar or to hold said fingers out of contact with said bar.

3. In a piano player, the combination of a box arranged to be held to the keyboard of a piano, electro-magnets within said box located to correspond to the white and black keys of the piano, blocks of different lengths on the front edge of the said box, key strikers hinged to said blocks and having their inner ends adapted to rest on the keys, the inner portions of the strikers attached to the longer blocks being arched to clear the white keys and engage the black keys, armatures secured to the under sides of the key strikers, and note - sheet - controlled circuit - closers electrically connected with the electro-magnets.

4. The combination of feed rollers, a convex guide bar adjacent to the feed rollers, a conductor bar secured on the rear edge of the guide bar, contact fingers pivoted above the guide bar and arranged to rest on said conductor bar, a yieldingly-held angular rock bar bearing against the contact fingers, a series of key strikers, and a series of electro-magnets controlling the key strikers and in circuit with the conductor bar and the contact fingers.

In testimony whereof I affix my signature, in the presence of two witnesses.

WESLEY B. KRAFT.
